UNITED STATES PATENT OFFICE.

JOSEPH SUNNEN, OF ST. LOUIS, MISSOURI.

VALVE LIFTER.

Application filed August 9, 1921. Serial No. 490,968.

To all whom it may concern:

Be it known that I, JOSEPH SUNNEN, a citizen of the United States, residing at city of St. Louis, State of Missouri, have invented 5 a certain new and useful Improvement in Valve Lifters, of which the following is a full, clear, and exact description, such as will enable others skilled in the art to which it appertains to make and use the same, reference being had to the accompanying drawings, forming part of this application.

My invention relates to valve lifters and is an improvement upon the valve lifters disclosed in United States Letters Patent No. 15 1,369,142 dated February 22, 1921.

The objects of the present invention are to provide a valve lifter of the class disclosed in the above patent and provided with oppositely disposed adjusting members seated 20 in and projecting outwardly from the opposite ends of each jaw and adjustable so that said jaws can be contracted and expanded laterally.

Further objects of my invention are to 25 provide a tubular member nonrotatably seated in one end of the jaw and having threaded engagement with the threaded end of an adjusting screw rotatably seated in the opposite end of said jaw, said tubular member and said adjusting screw projecting inwardly from said jaw whereby the outer sides of the jaws are devoid of any projections large enough to interfere when the device is being used.

Still further objects of my invention are 35 to generally improve and simplify the construction, and cheapen the cost of manufacture and assembling of valve lifters of the class described.

With the foregoing and other objects in view, my invention consists in certain novel features of construction and arrangement of parts hereinafter more fully described and claimed in the accompanying drawings, in 45 which—

Figure 1 is a side elevation of a valve lifter of my improved construction.

Figure 2 is a top view of the same.

Figure 3 is a vertical cross section taken 50 on the line 3—3 of Figure 1.

Figure 4 is a detail perspective view of the tubular threaded member and a portion of the jaw showing the seat therefor.

Referring by numerals to the accompanying drawings, 10 designates the upper jaw member comprising substantially parallel

ends 11 connected at their rear portions by a base plate 12. Projecting forwardly from this plate and disposed below said ends 11 are a pair of lugs or ears 14 to which is 60 pivotally mounted by means of pin or rivet 15 the lower jaw member 16 which comprises substantially parallel ends 17 having a rear or base portion 18. This base portion has an upwardly extending projection 65 19 which occupies a position between the ends 11 and immediately in front of the base plate 12. A screw 20 has threaded engagement with the base plate 12 and the threaded end thereof projects forwardly and 70 inwardly within jaw member 10 and bears against the upward projection 19 of the lower jaw member 16.

In order to provide sufficient bearing for 75 screw 20, an internally threaded tubular member 21 can be fixed to the base plate 12 to form a threaded seat for screw 20. The outer or free end of screw 20 is provided with suitable projections 22 whereby said screw can be conveniently manipulated. The 80 lower edges of ends 11 are turned inwardly to form horizontally disposed flanges 11^a which are adapted to engage a spring washer carried by the lower stem of a valve stand. The lower edges of ends 17 of jaw member 85 16 are provided with horizontally disposed inwardly projecting flanges 17^a which are designed to rest on the portion of the cylinder casting immediately below the valve 90 stem or on parts associated with the valve 95 push rod.

Inasmuch as the valves of the various makes of automobiles vary in size and the space available for positioning the lower jaw adjacent to the push rod varies, in some cases 95 being very limited, provision is made for adjusting the ends of the jaws laterally by means projecting inwardly from said ends so as to leave the outer walls thereof free 100 from any projections which might interfere with the proper and efficient functioning of the valve lifter. These means consists of screws 24, the heads of which are rotatably mounted in one end of each jaw, the threaded portions of said screws extending inwardly 105 towards the opposite ends of the respective jaws. These threaded ends are screw seated in tubular members 25 detachably carried by the opposite ends of the jaws by means of shank portions 26 formed integral with 110 tubular members 25 and seated in seats 27 formed in the corresponding ends of said

jaws. In order to retain tubular members 25 in their respective positions, the ends 26^a of shank portion 26 are bent transversely so as to bear against the outer walls of the 5 jaw ends in which shank portions 26 are seated.

In the operation of my device, the valve lifter is placed in position, as shown in Figure 1, with the ends 17 of the lower jaw resting 10 on the cylinder casting or other stationary support and the ends 11 of the upper jaw 10 engaging the underside of the spring washer fixed to the valve stem of the valve which it is desired to lift. By turning screw 20 in 15 the proper direction, jaw member 10 is caused to rock on the pivot 15 so that the ends 11 are moved upwardly to compress the valve spring and raise the valve stem and the valve carried thereby.

20 In order to adjust laterally the ends 11 of jaw member 10 and the ends 17 of jaw member 16, screws 24 are turned in proper direction causing the ends of the respective jaw members to move towards each other, 25 and vice versa, by virtue of the fact that the threaded end of each screw 24 is in threaded engagement with the tubular member 25 non-rotatably carried by the opposite end of the respective jaw.

30 A valve lifter constructed according to my invention is inexpensive to manufacture, can be easily and quickly assembled, and having no outward projections on its valve engaging ends, can be used in engines having very 35 restricted space in which to operate.

It will be readily understood that minor changes in the size, form and construction of the various parts of my improved "valve lifter" may be made and substituted for 40 those herein shown and described, without departing from the spirit of my invention, the scope of which is set forth in the following claims.

I claim:

45 1. A valve lifter comprising a pair of jaws pivotally connected at their base portions, means carried by one of said jaws and operatively engaging the other jaw for moving said jaws about their pivotal connection, and 50 means seated in the opposite ends of each jaw and projecting inwardly therefrom to-

ward each other to form operative engagement for adjusting the ends of each jaw laterally.

2. A valve lifter comprising a pair of 55 U-shaped jaw members pivotally connected at their base portions, means screw-seated in the base portion of one of said jaws and engaging the base portion of the other jaw whereby said jaws can be adjusted relative 60 to each other, a member rotatable in one end of each jaw and projecting inwardly towards the opposite end, an inwardly projecting member non-rotatably seated in said opposite end of each jaw and in threaded engagement with said rotatable member whereby the respective ends of each jaw can be adjusted laterally relative to each other by manipulating said rotatable member.

3. A valve lifter comprising a pair of 70 U-shaped jaw members pivotally connected adjacent to their base sections, an adjusting member screw-seated in the base section of the outer jaw member and having its inner end engaging the base portion of the inner 75 jaw member whereby said jaw members can be adjusted relative to each other, a threaded member rotatably carried by one end of each jaw member, and a tubular member non-rotatably carried by the opposite end of 80 each jaw member and in threaded engagement with its corresponding threaded member, whereby by the turning of said threaded member, the ends of each jaw can be adjusted laterally.

4. A valve lifter comprising a pair of 85 U-shaped members pivotally connected adjacent to their base portions, means for adjusting said U-shaped members, relative to their pivotal connection, a rotatably threaded 90 member extending inwardly from one end of each jaw member, and an internally threaded sleeve adapted to receive the threaded end of said rotatable member and provided with a shank portion non-circular 95 in cross section which engages a non-circular seat formed in the opposite end of each jaw member.

In testimony whereof I hereunto affix my signature this sixteenth day of July, 1921. 100

JOSEPH SUNNEN.
